UNITED STATES PATENT OFFICE.

CHARLES KIWUL, OF NEW YORK, N. Y.

MOTION-PICTURE MACHINE.

Application filed July 3, 1919. Serial No. 308,642.

To all whom it may concern:

Be it known that I, CHARLES KIWUL, a citizen of Russia, and resident of New York city, in the county of New York and State of New York, have invented certain new and useful Improvements in Motion-Picture Machines, of which the following is a specification.

The invention relates to a motion picture machine of the type in which the picture film is passed across the beam of light with a continuous motion.

The primary object of the invention is to provide an improved form of machine of the type above defined and in which the picture is maintained steady on the display screen free of the objectionable flicker so objectionable in motion picture machines of the type in which the film is fed intermittently.

Broadly, this object is attained by causing the light projected through succeeding picture units on the film of the continuously travelling film to be reflected alternately along two separate paths and both eventually directed to the same place as to superimpose the succeeding images in the sequence in which they appear on the film.

Incidental to this last desideratum it is another object of the invention to provide a lens construction which will compensate for the motion of the picture film and which will travel with the film at a speed relative thereto so as to maintain the projected image fixed on the screen.

Another object of the invention is to provide a simple form of the device of the class disclosed in which the several movable parts may be adjusted to insure proper focus and the like.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:

Figure 1 is a view in side elevation of a portion of a motion picture machine constituting a preferred embodiment of the invention;

Figure 2 is a horizontal sectional view taken on the line 2—2 of Figure 1;

Figure 3 is a side elevational view of the device looking at a portion of the same as seen from the left hand side of Figures 1 and 2 with the front lens removed;

Figure 4 is a longitudinal sectional view of one of the lens constructions shown in the preceding figures;

Figure 5 is a plan view of the device shown in Figure 4;

Figures 6 to 9, inclusive, are detailed views of the lens carriage shown in Figures 4 and 5; Figure 6 being the plan view of the carriage demounted from the carrying bar; Figure 7 being a transverse sectional view taken on the line 7—7 of Figure 6; Figure 8 being a plan view of the bearing block and which is mounted in the socket shown in Figure 6 and Figure 9 being a transverse sectional view taken on the line 9—9 of Figure 8;

Figure 10 is an enlarged sectional view taken on the line 10—10 of Figure 3 and with certain of the parts as shown diagrammatically;

Figure 11 is a side elevational view of the device shown in Figure 10;

Figure 12 is a vertical sectional view taken through the guide blocks shown in Figure 3 and taken on the line 12—12;

Figure 13 is a diagrammatic showing of the movable reflectors, on a scale larger than that shown in Figure 3; and Figure 14 is a transverse sectional view taken on the line 14—14 of Figure 11.

In the following description and in the claims, parts will be identified by specific names for convenience of expression but they are intended to be as generic in their application to similar parts as the art will permit.

In the accompanying drawings, there is shown a bed-plate 10 having an extension 11' at one side thereof constituting a lamp base for carrying the source of light (not shown) as is usual in such constructions. A relatively massive standard 11 projects upwardly from the top of the base and constitutes a support for the film supply reel 13. A take-up reel 14 is suspended from a bracket 15 positioned on the underside of the bed-plate 10 and below the reel 13. A mechanism supporting bracket 16 is demountably fastened to the standard 11 and provides a support adjacent its upper end for a freely

rolling guide sprocket 17 and a take-up sprocket 18 constituting continuously acting

film actuating mechanism for drawing the film 19 from the supply reel 13 to pass the same continuously across the aperture 20 in an aperture plate 21 and finally to pass the film onto the take-up reel 14 as is usual in devices of this type in which the film is caused to be moved continuously in distinction from the intermittent feed across the aperture plate as is usual in well known forms of such devices.

The film is of the conventional type and includes a series of succeeding picture units 22 (see Figure 3) having the usual length between the succeeding dividing lines 23. The length of the picture units, that is the distance between succeeding lines 23, will be referred to hereinafter as unit picture lengths. The bracket 16 is provided with a U-shaped extension 24, the front portion of which constitutes the aperture plate 21 and which extension is demountably fastened to the bracket by screws 24'. An endless belt of moving reflectors 25 are mounted to move periodically across the primary optic axis $a-b$ of the machine centered in the aperture opening 20. The reflectors are of the triangular prism type and are positioned in hollow frames 26 fixed to the outer side of an endless belt 27. This belt is passed about vertically spaced apart sprocket wheels 28 mounted upon shafts 29 journaled at opposite ends within the bracket 16 and its extension 24 as shown more particularly in Figure 1. The reflectors are spaced apart longitudinally of the belt and have a length substantially equal to the picture unit length, hereinafter defined. The reflectors are spaced apart a distance so that when moving across the optic axis they will be spaced apart a distance substantially equal to said unit picture length. The reflectors move in a synchronism with the picture film and are so positioned that a reflector will be opposite each alternate picture unit in the film when the film picture and the movable reflectors are passing across the aperture. A stationary reflector 30 similar to the movable reflector is positioned in the primary optic axis $a-b$ and beyond the path of travel of the movable reflectors. The reflectors, both stationary and movable are disposed to reflect the light impinged thereon in the same general direction to one side of the machine. In some cases it may be desirable to place in the path of light additional reflectors 31 and 32 in such positions as to make the total length of the path of the light from the film to the screen when reflected from the moving reflectors equal to the length of the path of light and reflected from the stationary reflector. The reflector 31 faces the movable reflectors when positioned in the primary optic axis and the reflector 32 faces the stationary reflector 30. Tracing out the path of light reflected out of the primary

axis by the movable reflectors it is seen from Figure 2 that the light is bent at right angles, is directed along the left secondary optic axis $c-d$ if the mirror 31 is used thence along the screen optic axis $d-e$. Similarly the light reflected from the primary optic axis by the stationary reflector along the optic axis $b-f$ to the mirror 32, if it is used, and thence along the screen optic axis $f-g$ to the display screen. The movable reflectors are moved at the same speed as the film and to insure this cooperation the carrying belt 27 is driven from the power mechanism which drives the film. This mechanism includes a main shaft 33 provided with a driving pulley 34 at one end and by means of which the machine may be operatively connected to some suitable motor to drive the same. In the alternative the mechanism may be actuated manually from a power shaft 35 through the rotation of the handle 36. The shafts 33 and 35 are connected through the meshed gearing 37. The shaft 35 carries the pulley 106 at one end thereof so as to actuate the take-up mechanism and is also operatively connected to drive the movable reflector belt. This connection is provided by means of the bevel gear connection 38, which drive from the shaft 35 through the bevel gears 39, the last element of which is fastened to an extended part of the shaft 29 carrying the lower of the sprockets 28. By this means the rotation of either of the shafts 33 or 35 will move both the film and the reflectors in unison and at the same speed across the primary optic axis.

A series of travelling lens constructions 40, hereinafter specifically referred to as the left-hand lens construction, is mounted to move the lenses across the optic axis $c-d$ and similarly a right-hand lens construction 41 is similarly designed to move a series of lens across the optic axis $b-f$. As these constructions are similar in form except for the reversal of positions, the detailed description of the left series will be sufficient for the right hand series except for obvious changes in position. The lens construction 40 is mounted upon a shiftable base plate 42 positioned on the plate 10. A pair of uprights 43 project upwardly from and are movable with said base plate. A lens actuating shaft 44 is journaled in the uprights and is free to move longitudinally for a limited distance in its bearings in the support 46. The shaft is driven from the main shaft 33 through the gear train 45, the last member of which is keyed to the shaft 44 so as to drive the same in its different positions. The gear train is mounted in a support 46 fixed to the plate 10 which support also forms an end bearing for the main power shaft 33. A lens guiding block 47 is fixed to a supporting bar 48 which is slidably mounted in said uprights and is held in adjusted position therein by a set 130

screw 49. This bar also extends through the support 46 and is secured thereto by a set screw 50. The block is of a frusto-conical form substantially elliptical in cross-section 5 with opposite sides flat, as shown in Figure 12 and provided with a pair of annular guiding slots 51 and 52.

A pair of chain driving sprockets 53 and 54 are fixed to the shaft 44 adjacent the inner 10 sides of the uprights 43. These uprights also provide supports for a pair of idler sprockets 55 and 56 disposed respectively above the sprockets 53 and 54. The sprockets 53 and 55 are of a larger diameter than the sprockets 15 54 and 56. A relatively long chain 57 is passed about the sprockets 53 and 55 and a relatively short chain 58 is passed about the sprockets 54 and 56. A plurality of flat lens supporting bars 59 herein shown to be 20 four in number, extend between and are fastened at opposite ends to the chains by means of flexible joints 60 which permit movement of the bar in two planes at right angles to each other relative to the chains as 25 shown in Figure 5.

A lens frame 61 carrying a lens 62 is slidably mounted on each of said bars. The frame is provided with a cover 63 having a pair of ribs 64 and 65 extending therefrom 30 and adapted to engage in the slots 51 and 52 as the lens constructions are revolved about the guiding block 47.

The bar 59 is contained within a slot 66 formed on the underside of the cover and 35 which slot enlarges in cross-section from the center towards opposite ends thereby to permit rotary movement of the frame relative to the bars. This freedom of relative rotary movement is facilitated by journalling 40 a turntable 67 at the center of the slot and mounting the bar slidably in a slot 68 formed in the turntable. The lens 62 is not of conventional form but is quadrangle in plan instead of the usual circular form. The distance 45 between the centers of the sprockets 54 and 56 is smaller than the corresponding distance between the sprockets 53 and 55. The relative sizes and distances are chosen so that the chain 57 makes a complete revolution 50 in the same time as the shorter chain 58. This latter chain being shorter moves with a speed less than the speed of the longer chain 57. The difference in speed of the two chains is chosen so that one moves faster 55 and the other moves slower than the lens should move in order to compensate for the motion of the film and to maintain the resulting picture steady on the screen.

The speed of the objective lenses may be 60 adjusted by fastening the set screw 50 (Figure 3) loosening the set screw 49, and then shifting the plate 42. The shaft 44 slides in the support 46 and in the gear 45 to which it is operatively connected. The lenses are held in position by the block 47

through the medium of the slots 51 and 52 engaging the ribs 64 and 65. As one of the chains is moved closer to the guiding block 47, the other chain recedes from the block and by this means the speed of the lenses is 70 caused to approach the speed of that chain which is moved towards the lens. In this way the speed of the lenses is varied within certain limits independently of the speed of the film. 75

If the set screw 49 is fastened, the set screw 50 loosened, and the plate 42 shifted, then the whole system of lenses, the chains 57 and 58, and their supports, moves as a unit without affecting the speed of the lenses. 80 In this way the distance between the objective lenses and the picture film is varied, and thus the picture can be focused on the screen. The base 42 is fastened in position to the main base 10 by means of the slot and screw 85 69.

The lens frames are steadied in their path of movement across the secondary optic axis by an engagement with upstanding guides 70 and 71 positioned on the outsides 90 of the path of movement of the bars 59. The bars are each provided with wings 72 extending laterally from adjacent ends thereof and are designed to engage in slots 73 (see Figures 10, 11 and 14) in the upstanding guides 70 and 71. The parts are so proportioned that the wing ends travelling in the slots will cause the lens to move steadily across the secondary optic axis. For the purpose of facilitating the movement of 100 the lens from the rectilinear path and about the top and bottom of the guide block 47, an inverted U-shaped tripping member 74 is pivotally mounted above the guide block on the extension 75 from the support 43. 105 One arm 76 constitutes a receiving arm and is provided at its lower end with an out-turned finger 77 for engaging the outer side of the wings as their associated lens constructions move towards the top of the guide 110 block.

The other arm 78 is relatively shorter so as to permit the advance edge of the wing which is shorter than its rear arm to clear the lower end of the arm and permit the 115 rear edge of the wing to engage this arm 78 as shown in Figure 10. A spring 79 acts on the U-member to maintain the same normally in position and pins 80 and 81 act to limit abnormal swinging movement of said 120 U-member. The movement of the lens constructions from their rectilinear to their succeeding circular paths and vice versa is additionally facilitated and shock on the system minimized by means of a plunger 82 125 positioned in a recess 83 drilled through the guide block at the place where the lens frame engages the guide block adjacent its upper portion. The plunger is maintained in projected position by means of a spring 84 and 130

is connected through the recess by means of a coiled spring 85 with a second plunger 86 on the opposite side thereof. This second plunger is normally flush with the side of the block 47 so as not to interfere with the movement of the lens construction. By this construction it is understood that as the lens construction moves into the position on the downward movement as shown to the left of Figure 10, the impact of the lens frame engaging the guide block is cushioned by the plunger 82 and any excessive impulse imposed on this plunger will be transmitted through the spring 85 and imparted to that lens frame on the opposite side which is just about to leave its rectilinear path. The plunger 86 acts upon this oppositely disposed lens frame to push the same into its circular path at the top of the guide block.

It has been shown that the speed of the objective lenses may be varied by moving the two plates 42 upon which the two sets of lens constructions are mounted. Under some conditions it may be desirable to adjust both plates 42 simultaneously and for this purpose a manually actuated shaft 87 is arranged to be connected at will to both of the plates. The shaft is provided at its front end with a finger piece 88, projecting forwardly of the machine, as shown in Figure 1. A pair of pinions 89 and 90 are mounted upon this shaft and each pinion engages respectively with racks 91 and 92 constituting part of each of the plates 42. The pinions are provided with hubs which are fastened to the shaft by means of set screws 93 and 94 so arranged that with the two set screws tightened the rotation of the shaft will shift both of the lens constructions. With one of the hubs loose on the shaft, the actuation of this shaft will move the plate associated with the fixed hub, thereby providing for relative movement between the two sets of lens construction.

The synchronizing of the movements of the left and right hand set of objective lens constructions is accomplished by mounting the actuating gears in proper positions on their respective shafts. Further means are provided to correct any inaccuracy in phase due to mounting or due to other causes. For this purpose the shaft 95 in the right hand series of objective lens constructions, corresponding to the shaft 44 hereinbefore described, is made in two parts split along the line 96. A sleeve 97 telescopes the adjacent ends of the shaft and is connected to one of the parts of the shafts by a pin and slot connection 98 in which the slot extends longitudinally. The sleeve is likewise connected to the other part of the shaft by means of a pin and slot connection 99 in which the slot is inclined at an angle to the axis of the shaft. The sleeve is thus free to revolve with the shaft and is engaged by a nut 100

carried on a feed screw 101, mounted in a bracket 102, constituting an extension from the support 46. It is obvious that by rotating the feed screw the sleeve will be moved longitudinally of the shaft and this action will shift the part of the shaft carrying the lens construction relative to the gear train 103, which connects the shaft 95 with the gear train 45. By this means one of the lens constructions is advanced or retarded in phase relative to the other lens construction. An adjustment 104 similar to the pin and slot connection 98 connects the two parts of the shaft and is actuated by a lever 105. By shifting the lever the film is adjusted relative to the aperture opening and the picture unit is thus framed.

In operation and assuming that the parts are in the position shown in Figure 1, with the film travelling continuously across the primary optic axis at the aperture opening and that the several parts of the movable reflectors and the corresponding parts of the lenses are travelling in the proper timed relation described, it is understood that the light from the source will pass through the succeeding picture units on the film. Assume first that at one moment a unit is framed in the opening at the time a movable reflector is in the primary optic axis; then the light passing from this movable reflector is projected through the objective lens which happens to be in position to receive the same. It is understood that the movable reflector and the movable lens travel with the picture as long as any part of the picture unit is facing the aperture plate. By the time the picture unit under discussion has passed beyond the aperture opening the movable reflector has likewise passed beyond the aperture opening and the light projected through the succeeding picture unit is reflected from the fixed reflector through the objective lens of the right hand set of objectives, which by this time is moved into position to receive the same. In this way each succeeding picture is projected, one through the left hand set of objectives onto the screen and the next through the right hand set of objectives onto the screen.

By means of a device of this character it is possible to focus the picture on the receiving display screen and to permit the film to travel continuously and without intermission through the motion picture machine, hereinbefore described. The picture is maintained steady on the screen and without objectionable flicker or other disagreeable optic effect.

While I have shown and described, and have pointed out in the annexed claims, certain novel features of my invention, it will be understood that various omissions, substitutions and changes in the form and de-

tails of the device illustrated and in its operation may be made by those skilled in the art without departing from the spirit of the invention.

6 Having thus described my invention, I claim:

1. In a motion picture machine, the combination with a film actuating mechanism for causing the film to move continuously across the optic axis of the machine, of a stationary reflector disposed in the optic axis of the machine and in advance of the film path, a continuously moving reflector mounted to move across the optic axis of the machine in advance of the path of movement of the film and in between the stationary reflector and the film path, said movable reflector having a rectilinear movement parallel to the direction of movement of the film thereby to travel with one of the picture units on the film as it moves across the optic axis, additional reflectors facing both the stationary reflector and the movable reflector disposed to combine the picture images reflected from the stationary and movable reflectors on to a display screen, and objective lenses operatively associated with said reflectors to focus the picture images on the screen.
2. In a motion picture machine, the combination with a film actuating mechanism for causing the film to move continuously across the optic axis of the machine, of a stationary reflector disposed in the optic axis of the machine and in advance of the film path, a series of spaced apart reflectors movable successively across the optic axis of the machine between the path of movement of the film and the stationary reflector, said movable reflectors having a rectilinear movement parallel to the direction of movement of the film and disposed when so moving to face each alternate picture unit on the film, said movable reflectors being spaced apart a distance to permit the light passing through the other picture units to pass between succeeding movable reflectors and be reflected from the stationary reflector.
3. In a motion picture machine, the combination with a film actuating mechanism for causing the film to move continuously across the optic axis of the machine, of a stationary reflector disposed in the optic axis of the machine and in advance of the film path, a series of spaced apart reflectors movable successively across the optic axis of the machine to one side of the path of movement of the film, said movable reflectors having a rectilinear movement parallel to the direction of movement of the film and disposed when so moving to face each alternate picture unit on the film, said movable reflectors being spaced apart a distance to permit the light passing through the other picture units to pass between succeeding movable reflectors and be reflected from the stationary reflector and means facing the stationary reflector and facing the position of the active movable reflector when passing across the optic axis for combining the images from both the stationary and the active movable reflector.
4. In a motion picture machine, the combination with a film actuating mechanism for causing the film to move continuously across the optic axis of the machine, of a stationary reflector disposed in the optic axis of the machine, a series of spaced apart reflectors movable successively across the optic axis of the machine in advance of the path of movement of the film, said movable reflectors having a rectilinear movement parallel to the direction of movement of the film and disposed when so moving to face each alternate picture unit on the film, said movable reflectors being spaced apart a distance to permit the light passing through the other picture units to pass between succeeding movable reflectors and be reflected from the stationary reflector and means facing the stationary reflector and facing the position of the active movable reflector when passing across the optic axis for combining the images from both the stationary and the active movable reflector, and a pair of lens constructions, one disposed in the part of the optic axis between the stationary reflector and said last named image combining means and the other lens construction disposed in the part of the optic axis between the active movable reflector and said last named image combining means.
5. In a motion picture machine, the combination with a film actuating mechanism for causing the film to move continuously across the optic axis of the machine, of a stationary reflector disposed in the optic axis of the machine and in advance of the film path, a series of spaced apart reflectors movable successively across the optic axis of the machine in advance of the path of movement of the film and between the stationary reflector and said path, said movable reflectors having a rectilinear movement parallel to the direction of movement of the film and disposed when so moving to face each alternate picture unit on the film, said movable reflectors being spaced apart a distance to permit the light passing through the other picture units to pass between succeeding movable reflectors and be reflected from the stationary reflector and a pair of lens constructions, one operatively disposed to affect the images reflected from the stationary reflector and the other operatively disposed to affect the images reflected from the movable reflector when disposed in active position in the optic axis of the machine.
6. In a motion picture machine, the com-

- combination with means for causing a film to move continuously across the optic axis of the machine, of means for affecting the light rays passed through said film, said means including in order along the optic axis, a movable reflector travelling in the direction of travel of the film for momentarily reflecting the light to one side, a stationary reflector for similarly reflecting the light when the movable reflector is clear of the optic axis, an organization of lens constructions for affecting the light reflected from both the stationary and movable reflectors.
7. In a motion picture machine, the combination with means for causing a film to move continuously across the optic axis of the machine, of means for affecting the light rays passed through said film, said means including light bending elements comprising in order along the optic axis, a movable reflector travelling in the direction of travel of the film for momentarily reflecting the light to one side, and a stationary reflector for similarly reflecting the light when the movable reflector is clear of the optic axis.
8. In a motion picture machine, the combination with means for causing a film to move continuously across the optic axis of the machine, of means for affecting the light rays passed through said film, said means including in order along the optic axis, a movable reflector travelling in the direction of travel of the film for momentarily reflecting the light to one side, a stationary reflector for similarly reflecting the light when the movable reflector is clear of the optic axis, and two sets of lens constructions, each set including a plurality of lenses and each lens mounted to move across the optic axis of its correlated reflector.
9. In a motion picture machine, the combination with a film actuating mechanism for moving the film picture units across the optic axis of the machine, of means for reflecting the images formed by certain of the picture units, said means including an endless belt, a plurality of reflectors disposed on said belt in spaced apart relation longitudinally of the belt, said reflectors spaced apart distances at least equal to the length of the picture units and each reflector having a reflecting length substantially equal to the length of the picture units, said reflectors when moving across the optic axis being disposed parallel to the path of movement of the film and facing the picture units which are to be reflected and a common driving means for actuating the film actuating mechanism and the reflecting means.
10. In a motion picture machine, a support, a pair of members rotatably mounted in said support, one of said members being in the form of a driving sprocket wheel, a belt passed about said members and engaged by said driving sprocket wheel, a plurality of reflectors mounted in longitudinally spaced apart relation on said belt and movable with the belt across the optic axis of the machine and a movable lens construction operatively associated with the belt to move constantly in one direction with the reflectors.
11. In a motion picture machine, the combination of mechanism for advancing the film continuously through the machine, a movable reflector operatively connected to move with the film and an objective lens construction including a plurality of lens operatively connected to said mechanism to move continuously in one direction over a substantially elliptical path, certain of said lens when in a portion of said path travelling with the light reflected from said movable reflector.
12. In a motion picture machine, the combination of a mechanism for causing the picture film to move continuously through the machine and form picture images on a screen, a pair of travelling lens constructions, each operatively connected with the film actuating mechanism to move therewith, means for directing succeeding images alternately through the two lens constructions and means for guiding said moving lens construction in one direction over a continuous path, a portion of which extends in a straight line at right angles across the two optic axes provided by said image-directing-means and at a speed corresponding to the speed of the pictures as they pass across said optic axes.
13. In a moving picture machine, the combination of mechanism for causing the picture film to move continuously through the machine, two sets of reflectors, one of said sets being fixed relative to the optic axis of the machine and the other set being movable across said axis, two sets of objective lenses, one movable across the secondary optic axis caused by the reflection of light from the stationary reflector and the other set being movable across the secondary axis similarly created by said movable reflector, mechanism operatively connecting said two sets of objective lenses with the film actuating mechanism whereby the lenses are caused to move in synchronism with the film.
14. In a moving picture machine, the combination of mechanism for causing the picture film to move in one direction, two reflectors, one fixed relative to the optic axis of the machine and the other movable periodically across said axis and in the direction of movement of the film, two movable objective lenses disposed for movement respectively across the secondary axes created by the light reflected from said two reflectors.
15. In a moving picture machine, the combination of mechanism for causing the picture film to move continuously through the machine, a movable reflector operatively connected to move with the film and an objective lens construction including a plurality of lens operatively connected to said mechanism to move continuously in one direction over a substantially elliptical path, certain of said lens when in a portion of said path travelling with the light reflected from said movable reflector.

combination of mechanism for causing the picture film to move in one direction, two reflectors, one fixed relative to the optic axis of the machine and the other movable periodically across said axis and in the direction of movement of the film, two movable objective lenses disposed for movement respectively across the secondary axes created by the light reflected from said two reflectors and means for combining the images produced by said two objective lenses.

16. In a moving picture machine, the combination of mechanism for causing the picture film to move continuously through the machine, a plurality of objective lenses movable across the optic axis of the machine, means for driving said lenses and means for varying the speed of said lenses relative to the speed of the film actuating mechanism.

17. In a motion picture machine, the combination of mechanism for causing the picture film to move continuously through the machine, means for reflecting the light passed through the film along two secondary optic axes, two sets of objective lenses, mounted for movement respectively across each of said optic axes and adjustable means for varying the speed of one set of the lenses relative to the other.

18. In a motion picture machine, the combination of mechanism for causing the picture film to move continuously through the machine, means for reflecting the light passed through the film along two secondary optic axes, two sets of objective lenses, mounted for movement respectively across each of said optic axes, adjustable means for varying the speed of one set of the lenses relative to the other, and means for varying the speed of either of the sets of lenses relative to the speed of the film.

19. In a moving picture machine, the combination of mechanism for causing the picture film to move continuously through the machine, means for reflecting the light passed through the film along two secondary optic axes, two sets of objective lenses, mounted for movement respectively across each of said optic axes and means for adjusting the position of said lenses thereby to focus the picture image on the screen.

20. In a motion picture machine, the combination of a lens guiding block having a straight guiding side, a series of lenses, means for guiding the series of lenses in its movement about said block, means for guiding each lens while moving along said straight side, means for causing a light ray to pass through the lenses while positioned on said straight guiding side and mechanism distinct from the lens guiding means and spaced from said block for assisting each lens in changing its direction of movement as it passes about said block and power

means for causing the lenses to travel about said block.

21. In a motion picture machine, the combination of a lens guiding block having a straight guiding side, a series of lenses guided for movement about said block, means for causing a light ray to pass through the lenses while positioned on said straight guiding side, means for causing the lenses to travel about said block and means for varying the speed of said lenses relatively to the speed of the film while passing across said light ray.

22. In a motion picture machine, the combination of a lens guiding block having a straight guiding side, a series of lenses guided for movement about said block, means for causing a light ray to pass through the lenses while positioned on said straight guiding side, means for causing the lenses to travel about said block and means actuated by the movement of one of the lenses for assisting another of the lenses to change its direction of movement as it passes about said block.

23. In a motion picture machine, the combination of a lens guiding block having a straight guiding side, a series of lenses guided for movement about said block, means for causing a light ray to pass through the lens while positioned on said straight guiding side, means for causing the lens to travel about said block and means for cushioning the lenses as it changes its direction of movement about said block.

24. In a motion picture machine, the combination of mechanism for moving the picture film continuously across a beam of light; a plurality of reflectors movable across said beam of light for directing the light issuing from one picture along a path different from the path along which the light issued from the preceding picture was directed, a plurality of objective lenses mechanism for moving said lenses at uniform speed and in a straight line across the paths of light reflected; and means for varying the ratio of the speed of said objective lenses to the speed of the film.

25. In a motion picture machine the combination of mechanism for moving a picture film continuously across a beam of light; means including a stationary reflector and a plurality of moving reflectors for directing the light issuing from one picture along a path different from the path along which the light issued from the next preceding picture was directed; a plurality of objective lenses and mechanism for moving said objective lenses in a straight line across the path of light so reflected.

26. In a motion picture machine the combination of mechanism to move the picture film continuously across the optic axis of the machine, lens actuating mechanism in-

- cluding two endless belts of different lengths adapted to move synchronously, a plurality of objective lenses connected to said endless belts to move at a speed which is a function of the speeds of the two belts; and means for varying the ratio of the speed of the objective lenses to the speed of said endless belts.
27. In a motion picture machine the combination of mechanism to move the picture film continuously across the optic axes of the machine, an objective lens having its axis at an angle to said optic axis, a reflector for directing the light from the picture to said lens mechanism including two endless belts of different lengths for moving the objective lens in a straight line and with uniform speed across the path of the light reflected from said reflector.
28. In a motion picture machine, the combination of mechanism for advancing the film continuously through the machine, a movable reflector, and an objective lens construction including a plurality of lenses operatively connected to said mechanism to move continuously in one direction over a substantially elliptical path, means for guiding the lens along said path, a portion of said guiding means being straight, said lenses when in an engagement with said straight portion of the guiding means travelling with the light reflected from said movable reflector.

Signed at New York city in the county of New York and State of New York this 29th day of May, A. D. 1919.

CHARLES KIWUL.
